METHOD AND APPARATUS FOR PREVENTING BACK-FIRES IN METAL VAPOR RECTIFIERS

Application filed May 29, 1926, Serial No. 112,665, and in Germany June 2, 1925.

This invention relates to the prevention of certain undesirable phenomena known as back-fires in apparatus for rectifying alternating current of the metallic vapor type, of which mercury vapor rectifiers are an example.

The general object of the invention is the prevention or elimination of such phenomena in a simple and reliable manner.

10 A particular object is the provision of a method and apparatus for the purpose stated, and which produces the desired preventive effect at such times when the tendency for the undesirable phenomena to take place is strongest.

20 Another object is the provision of a method and apparatus for the purpose stated which does not introduce parts into the interior of the rectifier which might themselves be the source of undesirable phenomena.

Other and further objects will be pointed out or indicated hereinafter, or be obvious to one skilled in the art upon an understanding of the invention.

25 In the drawings forming a part of this specification we show various arrangements of apparatus, the same being presented for the purpose of illustrating the invention. These are not to be construed in any fashion as having the effect of limiting the claims short of the true and most comprehensive scope of the invention in the art.

In the drawings,

Fig. 1 is a diagram of apparatus illustrating the invention,

Fig. 2 is a curve diagram illustrating the variation of the anode and shield potentials using the above apparatus,

Fig. 3 is a diagram of another form of apparatus illustrating the invention, and

Fig. 4 is a curve diagram showing the variation of anode and shield potentials using the apparatus of Fig. 3.

The operation of metal vapor rectifiers is liable to be interrupted by the occurrence of

back-fires (really internal short-circuits) which are usually accompanied by a number of other harmful effects. Thus a back-fire which ends in a dead short-circuit may have such a destructive effect on the material of the rectifier as to necessitate a complete shutdown. When a back-fire takes place, the current flows from the original cathode (or from one of the anodes) to an anode which has temporarily assumed the functions of a cathode, and it is therefore clear that a back-fire will usually tend to start during the time when the potential of the anode concerned is negative to that of the cathode. This condition is fulfilled during that portion of the cycle when the anode is not carrying a load current.

As a general rule the potential taken up by an insulated anode shield lies somewhere between the potentials of its associated anode and the cathode respectively. If an arc is struck from the anode, however, this forms a conducting path between the anode and its shield and the corresponding potentials will then be approximately equal.

Attempts have been made to suppress the back-fires by subdividing the anode shields or giving them certain shapes, but without success, the reason being that the mere presence of the shields cannot prevent the current from passing from cathode to anode. If a tendency to back-fire exists, the increasing glow-discharge current causes the anode shields to become positive with regard to the anodes so that the flow of current towards them is assisted.

The object of the invention is therefore a means for preventing back-fires in metal vapor rectifiers having insulated anodes, according to which insulated metal structures are arranged in the path of the back-fire discharge (these may be the anode shields themselves) are maintained at a potential negative to their associated anode over the period within each A. C. cycle during which

the said anode is not carrying load current. The potential of the metal structures referred to shall be applied in such a way that the anode is always positive to the metal structure or shields during the period of maximum tendency to back-fire.

Fig. 2 shows the variation of anode potential during a complete A. C. cycle. If the rectifier has six anodes for example, then 10 each carries the load current for one sixth of a cycle. This period is shown by t_1 and t_2 in Fig. 2. During this period the anode is positive with regard to the cathode. The horizontal line 1—1 represents the constant 15 potential of the cathode. It will be seen that outside the period t_1 — t_2 , the anode is negative to the cathode and hence there will be tendency to back-fire. If, however, the anode shield is maintained negative to the 20 anode during the danger period the shield will prevent an arc passing from the cathode to the anode, since the signs of the potentials in anode and shield respectively allow the passage of current in one direction only, i. e. 25 from anode to shield. The curve *b* in Fig. 2 shows the variation in the potential of the anode shield which should be obtained to secure the effect of the invention. In the example given it occupies a definite position 30 relative to the curve *a*, and may be arrived at by subtracting a constant amount *e* from the ordinates of *a*. The anode shield potential may be made to vary in the desired way by the following means:—The shields are all 35 connected to a special star-connected secondary winding of the transformer feeding the rectifier. This special secondary may be called an auxiliary secondary to distinguish it from the main winding. The auxiliary secondary may, for example, be wound 40 for the same voltage as the main secondary, but is quite independent of the latter and galvanically separated from it. Now in order to give the anode shields a negative potential 45 with regard to their respective anodes, a relatively low uni-directional potential drop is applied between the respective neutral points of the main and auxiliary secondaries, the sign of this potential drop being such that 50 the neutral point of the main winding will be positive to the neutral point of the auxiliary winding. The necessary potential drop may be obtained from a small motor generator, rectifier, or battery, and it should be 55 noted that only very small currents will be required.

This embodiment of the invention is illustrated in Fig. 1.

The three-phase mains N_w supply the primary P_1 of the transformer T feeding rectifier G , the transformer including a main secondary Q_1 connected as shown to the rectifier anodes a_1 — a_6 and an auxiliary secondary Q_2 connected as shown to anode shields h_1 — h_6 . 60 As will be seen from Fig. 1, the neutral

point o_1 of winding Q_1 , is joined to the neutral point o_2 of winding Q_2 through the battery B , o_1 being positive to o_2 . The negative wire of the D. C. system N_g starts from the rectifier cathode o_1 and the positive from K . In the example illustrated the anode shields h_1 to h_6 are insulated. If the voltage at the terminals of winding Q_1 is the same as that of winding Q_2 , then the potential of a shield will always be lower than that of the associated anode by an amount *e*. Thus a back-fire cannot start. On referring to the Figure 1 it will be seen that resistances w_1 to w_6 are inserted in the leads joining the anode shields with the terminals of the auxiliary winding Q_2 . These resistances may be ohmic, inductive, or capacitive, and their function may thus be explained:—The introduction of the potential drop *e* undoubtedly fixes the potential of the shields lower than that of the respective anodes. The shields however are bombarded by ions coming from the cathode and thus there will always be a reverse current flowing through the shields, outside the period t_1 — t_2 , which raises the potential of the same and may in certain circumstances neutralize the effect of the impressed voltage *e*. By inserting resistances as w_1 to w_6 this reverse current can be reduced to a negligible value.

One disadvantage of the arrangement described is the necessity for a supply of direct current. Suitable low voltage supplies are not always available, and in any case complicate the plant. The necessity for a D. C. supply may be entirely avoided, however, by making the voltage of the auxiliary secondary greater than that of the main secondary and not connecting the neutral points. It appears at first that the potential of the auxiliary winding and consequently that of the connected shields will still be indefinite, but as soon as an arc is struck between anode and cathode through the shield, the latter will take up the potential of the anode then carrying load current. During the period t_1 — t_2 (Fig. 2) therefore, the anode and associated shield are at approximately the same potential. The shields of the anodes not carrying current are then at a potential different from that of their respective anodes owing to the different voltages of the windings Q_2 and Q_1 , the shields being maintained at a lower potential than the anodes.

Fig. 4 gives the potential curves for this case, where *a* is the anode curve and *b* the shield curve. Over the period t_1 — t_2 the curves are coincident, owing to the arc forming a conducting path. Over the remaining parts of the cycle the curves diverge, the shield potential lying below the anode potential. The maximum divergence occurs at time t_3 when the curve *a* is at its maximum negative value and the difference *mn* is twice

the difference between the voltages of Q_1 and Q_2 .

Fig. 3 illustrates this arrangement diagrammatically. The same reference letters are used as in Fig. 1. The difference lies in the fact of winding Q_2 having more turns than winding Q_1 , so that the shields will be supplied with a higher voltage than the anodes, and also that the neutral points o_1 and o_2 are not connected. The potential of winding Q_2 is therefore entirely dependent on whichever anode is carrying load current at the time. Assume that an arc passes from anode a_1 through the shield h_1 to the cathode K. The shield h_1 will then take up the same potential as the anode a_1 . The potentials of the other shields will then depend on the magnitude and sign of the potential drops existing between the shields. It will be easily seen that in the case under consideration there must be a potential drop between the anode a_4 and shield h_4 which is given by the difference of two potential drops namely, the potential drop between the terminals 1' and 4' in winding Q_2 and the potential drop between terminals 1 and 4 in winding Q_1 . Since the potential drop between 1' and 4' is greater than the potential drop between 1 and 4 and 4, 4' are negative with regard to 1, 1 it follows that the shield h_4 must be negative with regard to the anode a_4 .

It has been assumed hitherto that the arc (load current) leaving the anode forms a conducting path between anode and shield and thus equalizes the potentials of both. With shields of certain shapes or sizes it may happen, however, that the arc does not come into contact with the shield at all, and its potential will therefore be indefinite. To ensure that both parts have the same potential the shields are given a certain degree of activity by allowing them to work as anodes on to a loading resistance. For this purpose a relatively large resistance is inserted between the neutral point o_2 of the winding Q_2 which supplies the shields, and the cathode. A small current then flows between the shields and the cathode, taking the form of an arc which unites with the main arc from the anodes. In this way the presence of an electrically conducting path between anode and shield is ensured.

In applying the foregoing method for preventing back-fires the effect of very small reverse currents on the shield potential must be taken into consideration. It must be assumed that a certain minimum reverse current is always passing. The effect of this reverse current is to raise the shield voltage and thus tends to counteract the externally impressed negative charge. There are various ways of rendering these reverse currents ineffective. For example, a smaller "control shield" can be fitted inside the anode shield proper and maintained at a potential some-

what lower than the anode. The outer shield then protects the control shield to a certain extent from radiation from the arc and thus prevents its potential being raised by the reverse current. Another way would be to provide either the inner or the outer shields, or both, with an insulating coating which must also surround the lead to the shield from the point where it enters the rectifier. This insulating covering would prevent reverse currents passing through the shields.

Finally, it is advisable to dispense entirely with all leads in the interior of the rectifier since back-fires are very liable to start from the lead-in points. This may be done by adopting a known design in which the anodes are housed in tubular members of non-metallic insulating material which extend outside the rectifier. The shield is then placed round the lower part of the tubular member and connected directly to the corresponding terminal of winding Q_2 . The resistances w_1-w_6 may then be dispensed with as no current can flow through the shields.

The anode shields may be replaced by other devices which when given a potential opposing the flow of current towards the anode eliminate the reverse currents. Equivalent devices may take the form of gratings, grids, rings etc., in short any insulated metal structure placed in the path of the back-fire discharge.

What we claim is:

1. In an electrical system of the character described, the combination with a polyphase metal vapor rectifier comprising anodes and shields associated respectively therewith, of means for impressing upon each shield a potential negative with respect to that on the respective associated anode during the entire non-working period of said anode.

2. In an electrical system of the character described, a polyphase metal vapor rectifier comprising anodes and shields associated respectively therewith, a polyphase winding supplying said anodes, and means for impressing upon each shield a potential negative with respect to that on the respective associated anode during a period of time immediately following each normal operating period of said anode, said means including a second polyphase winding.

3. In an electrical system of the character described, the combination with a polyphase metal vapor rectifier comprising anodes and shields associated respectively therewith, of means for impressing upon each anode and the associated shield similar sine waves of voltage characterized by the fact that at any instant of time the shield voltage is negative with respect to the anode voltage.

4. In an electrical system of the character described, a polyphase vapor rectifier comprising anodes and shields associated respectively therewith, a polyphase winding sup-

plying said anodes and having a neutral point, means for impressing upon each shield a potential negative with respect to that on the respective associated anode during a period of time immediately following each normal operating period of said anode, said means including a second polyphase winding having a neutral point, and a source of D. C. potential connected between said neutral points with the negative side of said source connected to the neutral point of said second polyphase winding.

In testimony whereof we have hereunto subscribed our names at Zurich, Switzerland on the 18th day of May A. D. 1926.
